(21) Appl. No.: **29/183,010**

(57) **CLAIM**

(22) Filed: **Jun. 5, 2003**

I claim the ornamental design for a light emitting diode, as shown and described.

(51) LOC (7) Cl. **13-03**

DESCRIPTION

(52) U.S. Cl. **D13/180**

(58) **Field of Search** D13/180, 182; D10/104, 114; 257/88, 89, 93–96, 98, 99, 678, 687; 313/498, 499, 555, 800; 361/820; 362/152, 226, 241, 249, 250, 800; 372/45; 439/353, 620

FIG. 1 is a perspective view of a light emitting diode showing my new design;
